PLATING TANK FOR ELECTRODEPOSITION
OF METALS ON METALLIC STRIP

William S. Allen, Pittsburgh, Richard A. Dimon, Dormont, and Ewart S. Taylerson, Pittsburgh, Pa., assignors to Carnegie-Illinois Steel Corporation, a corporation of New Jersey

Application April 28, 1939, Serial No. 270,702

1 Claim. (Cl. 204—206)

The present invention relates to a plating tank assembly for use in electrodeposition of metals on metallic strip.

An object of the present invention relates to the novel construction and arrangement of a vertically positioned tank for electrodeposition of metals on metallic strip.

Another object of the present invention is to provide an improved tank for electrodepositing metals on metallic strip in which the strip is so positioned and the electrolyte so circulated thereabout as to provide an improved electrodeposited surface on the resultant product.

A further object of the present invention resides in vertically positioning the anodes so that they are readily removable and capable of rearrangement across the width of the strip being plated to provide uniform deposition of the metal upon the surfaces of the strip.

A still further object of the present invention resides in providing a plating tank with a plurality of vertical pass lines whereby trappage of foreign matter on the surfaces of the strip material is minimized.

Other objects and advantages will become apparent as the description proceeds and reference is had to the accompanying drawings, in which:

Figure 1 is a sectional elevation of the apparatus of the present invention;

Figure 2 is a sectional elevation on the line II—II of Figure 1;

Figure 3 is a top plan view of the tanks showing the overflow system; and

Figure 4 is a fragmentary side elevation of Figure 3.

In the drawings, the numeral 2 represents a plating tank which includes side walls and a divided bottom portion. The bottom portion of the tank is so constructed and arranged as to include sloping side walls 3, the purpose of which is to direct any sediment downwardly so as to collect in the bottom of said tank, whereby such sediment may be easily withdrawn from said tank through the outlets 5. The top portion of the tank is offset outwardly from the side walls by a flange 6 with the upwardly extending flange 7 forming a trough at each end of the tank. These troughs form, in combination with overflow chambers to be subsequently specifically described, an overflow system necessary for the circulation of the electrolyte.

Positioned within the tank are segmental baffle members 8 adapted to divide the interior portion of the tank into a plurality of separate chambers or compartments. Within four of these compartments or chambers are positioned removable anodes 9 so as to provide four active vertically positioned plating areas through which the continuous strip material is moved in sequence. Between each of the active compartments is an inactive compartment containing electrolyte, but in which no plating reaction is effective upon the strip material. Positioned within two of the inactive compartments is a rubber covered pipe 26, the purpose of which will be subsequently explained. The anodes 9 are supported, by a bridge 10 extending across the top of the tank, in such a manner as to be readily removed from and/or rearranged across the plating tank if, when and as desired, to maintain efficient plating of the continuous strip. The feature of readily removing and/or rearranging the anodes as desired is of the type specifically shown and described in application Serial No. 270,708 entitled "Method and apparatus for supporting and replacing anodes" and filed April 28, 1939, in the name of Ewart S. Taylerson.

A supporting frame 16 is positioned above the plating tank and is provided with bearing brackets 17 which support conductor rolls 18. These conductor rolls may be supported, in any conventional manner, within the bearing brackets. The conductor rolls are preferably provided with a hard metallic protective surface or coating such as chromium and the like, and may be cooled, in any conventional manner, by circulating water throughout its interior. The connection between the conductor rolls and the negative side of the generator (not shown) is established, in any conventional manner, preferably by means of resiliently mounted electrical brushes, as disclosed in application Serial No. 270,706 entitled "Electrical conductor" and filed April 28, 1939, in the name of Ewart S. Taylerson.

The strip, in passing over the conductor rolls, is established as the cathode. In order that the best possible electrical contact may be maintained between the conductor roll and the strip, hold-down rolls 19 are provided. The hold-down rolls 19 are pivotally supported from a flange on the bearing bracket 17 by arms 20.

The hold-down rolls through the action of the turnbuckle arrangement 21 press the strip into positive contact with said conductor rolls. In order to facilitate threading of the machine, the turnbuckle arrangement 21, at its point of attachment to the arm 20 is provided with a disengaging mechanism consisting of an eccentric 22 mounted on a shaft 23 extending between

the arms 20 and operating within an eccentric strap 22 connected to the turnbuckle 21. The shaft 23 is provided with a hand-lever at one end thereof, and when this hand-lever is rotated the hold-down roll is moved either away from or into contact with metallic strip passing over the conductor roll. Disengagement of the hold-down roll permits initial threading of the strip material over said conductor rolls. When the hold-down roll is engaged, it establishes a positive contact between said conductor rolls and strip material. In establishing the desired positive contact, the hold-down roll is locked in position by the disengaging mechanism.

In addition to the hold-down roll 19, the entry conductor roll 18^a is provided with a squeegee roll 18^b, which roll prevents excess liquids carried on the surfaces of the strip from previous processing steps from being carried into the plating bath.

Sink rolls 13 are provided in the bottom of the plating tank and cooperate with the conductor rolls to form pass lines for the strip material. The sink rolls 13 are so positioned with respect to their cooperating conductor rolls that the distance from the center of a sink roll to the center of either of its cooperating conductor roll is, when measured in a horizontal plane, the sum of the radius of the sink roll and the radius of the cooperating conductor roll. Thus, the pass line of the strip between the rolls is in a vertical plane.

The sink rolls 13, which are rubber covered, are supported in the bottom of the tank in any conventional manner, and may be of conventional design. These rubber covered sink rolls are mounted, in any conventional type bearing supports, which may be either internal or external bearings and are of such a construction as to preclude entrance of the electrolyte within the bearing structure. Positioned within each sloping bottom portion 3 are several spaced guide plates 3^a, so shaped as to conform to the sloping bottom and the sink rolls 13.

These spaced guide plates 3^a cooperate with the sink rolls 13 so as to provide a channelway whereby the strip material may be guided around the bottom of the sink rolls during the initial threading operation of the strip material through the plating tank. These spaced guide plates 3^a are provided at their bottoms with a cut-out portion which permits the electrolyte to be drained when desired through the outlet pipes 5. Mounted in any conventional manner on the side of the plating tank adjacent the sloping bottom portions at spaced positions are rubber covered supports 12 adapted to serve as bearing supports for the closed ends of tubes 14, while the other ends of said tubes are supported by the opening which connects with the inlet feed pipe for the electrolyte. These tubes are provided with an open-14^a in order that the electrolyte may circulate upwardly within the active chambers or compartments formed by the segmental baffle members. The flow of electrolyte which is directed upwardly passes on both sides of the continuous strip. Attached to the walls of the respective chambers within the tank are trough-like members 15 provided at the bottom of each chamber containing the anodes so that any sludge or metallic particles developing from the anodes during the plating operation of the continuous strip material will be caught by said trough-like members 15 and prevented from dropping down between the strip

material and the sink rolls 13. The trough-like members 15 also serve to protect the tubes 14 from damage should an anode be dropped during anode renewal or rearrangement on the anode supporting bridge.

Secured on each side of the tank are two pre-formed rubber covered metallic members forming overflow chambers 25. These overflow chambers 25 extend upwardly from the side walls of the tank to a point in substantial alignment with the upper edge of the flange 7. A rubber covered pipe 26 which extends through the inactive pass chambers at a point adjacent the bottom of the overflow chambers 25, as previously described, connects the overflow chambers on each side of the tank so that the electrolyte may be withdrawn from the plating tank through the pipe 27. The electrolyte may then be settled, filtered, cooled or heated as desired, in any conventional manner, and returned by pumps or any other conventional apparatus to the pipes 14 for recirculation within the plating tank.

In operation of the present invention, the strip indicated generally as at S is fed from a previous processing device such, for example, as a washer or brushing machine and fed over the entry conductor roll 18^a. To initially permit threading of the strip material into and through the plating tank, the eccentric mechanism hereinabove described, is operated to release the hold-down rolls 19 so that the strip may be fed over and around the major portion of the entry conductor roll from which position it passes vertically downward into the pass line generally indicated at A between the anodes 9. As the strip is initially fed downward through the initial pass line A, it comes into contact with the guide members 3^a provided at spaced intervals in the sloping bottom of the plating tank, which guide members serve to direct the strip material around the first sink roll 13 and cause the same to move upwardly into the bottom portion of the pass line indicated generally at B. It is then pulled upwardly through the pass line B, passed over the second conductor roll and subsequently moved downwardly in a vertical plane through the pass line C, is guided around the second sink roll and up into the bottom of the pass line D, from whence it is pulled upwardly and over the last conductor roll and entered into further processing apparatus.

After this initial threading of the strip material, the hold-down rolls are moved into position to establish positive contact between the strip material and the conductor rolls. The electrolyte is then fed into the plating tank through the pipes 14 and upward circulation is established in the pass lines A, B, C and D on each side of the strip. The coating operation can now be started by simultaneously closing the electric circuits for supplying the necessary current for the plating operation and establishing movement of the material through the plating bath.

While we have shown and described a specific embodiment of the present invention, it will be seen that we do not wish to be limited exactly thereto, since various modifications may be made without departing from the scope of the invention, as defined by the following claim.

We claim:

In a plating tank for electroplating metallic strip, means for establishing the strip as the cathode, means for moving the strip in a substantially vertical path, a plurality of spaced ver-

tically extending anodes within said tank, means below the bottoms of said anodes for positively circulating the electrolyte upwardly on either side of the strip, said last-named means including a pair of spaced parallel horizontally extending pipes having on the adjacent sides thereof orifices for the distribution of electrolyte, and

guard means between said last-named means and the bottoms of said anodes for preventing damage by the accidental dropping of the latter.
